KONRAD NAGEL, OF NUEREMBERG, GERMANY, ASSIGNOR TO THE FIRM J. G. KAYSER
A. G., OF NUEREMBERG, GERMANY

EJECTING IMPLEMENT FOR COLD-PRESSED HEADED BOLTS

Application filed March 8, 1928, Serial No. 260,220, and in Germany March 19, 1927.

In the upsetting of heads on bolt shanks that have been cold-pressed in a closed matrix mounted upon an ejecting needle, the shank parts have been found by experience to become wedged so firmly in the bore of the matrix that a heavy pressure upon the ejecting needle is required to eject them. The ejecting needle is unsupported at the commencement of the ejection over a length which is at least equal to that of the bolt shank. On this part the needle is subjected to a buckling stress. It has been found by experience that this unsupported length must not be allowed to exceed about eight times the diameter of the shank because otherwise the needle buckles and breaks. Consequently with a closed matrix only headed bolts having shanks the length of which does not exceed eight times their diameter can be made. Headed bolts having a greater ratio of length to diameter must therefore be upset cold in a divided matrix. The shank becomes just as firmly wedged into the latter, but it nevertheless admits of being expelled by pushing the work-wire from behind, because one jaw of the matrix then yields under spring pressure transversely to the ejecting direction. The length of shank is here practically unlimited, but this method gives rise to a considerable and unavoidable disadvantage, in the form of radial burs or fins on the inner annular surface of the head, and the adjacent end of the bolt, originating from the matrix gap. These burs prevent a complete and satisfactory bearing of the head, and for most purposes they have to be removed by a special operation, carried out on special lathes. Such burs are not occasioned by the closed matrix, but with shanks the length of which exceeds eight times their diameter, the closed matrix cannot be used, for the reasons hereinbefore set forth.

The object of the present invention is to provide an ejecting implement that enables headed bolts which have been upset cold in a closed matrix and in which the length of the shank exceeds eight times its diameter, to be ejected without risk of breaking the ejecting needle. For this purpose the invention consists essentially in arranging behind the

closed matrix an undisplaceable sleeve which guides the ejecting needle and which also guides an intermediate piece which drives the ejecting needle before it, the guiding bore of the said sleeve being in connection with additional guiding ducts arranged in parallel with the said duct for the needle and adapted to form lateral supports for the intermediate piece, and the cross-sectional area of which conforms to the total cross sectional shape of the said guiding ducts and so great that the part of it which stands out rearwards at the beginning of the ejection without lateral support to an extent at least equal to the length of the shank cannot buckle under the pressure exerted by the push rod for the purpose of overcoming the jamming of the bolt shank.

The new ejecting implement is illustrated by way of example in the accompanying drawings, wherein

Fig. 1 is a rear view of the guiding sleeve, and

Fig. 2 a rear view of the intermediate piece to be guided therein.

Fig. 3 is a plan of the intermediate piece,

Fig. 4 shows the ejecting needle in plan, and

Fig. 5 the same in rear elevation.

Fig. 6 is a cross section through the intermediate piece and the sleeve guiding the same, and

Fig. 7 is a cross section through the ejecting needle and the sleeve.

Fig. 8 shows in longitudinal section the assembled ejecting implement fitted into the machine at the commencement of the ejecting operation, and

Fig. 9 shows the position of the parts of the implement at the termination of the ejecting operation.

Fig. 10 shows a different cross-sectional form of the sleeve and of the intermediate rail.

a is the closed press matrix, *b* the matrix cover, *c* the anvil, *f* the machine body, and *o* the push rod guided therein. Up to this point the upsetting apparatus is substantially known. From known upsetting appliances with closed matrices the present apparatus is distinguished merely by the exceptionally

great length of the matrix in comparison with the thickness of the bolt. The bore thereof, not shown, takes a shank s , the length l of which is more than eight times as great as its thickness d . While the shank is mounted upon the ejecting needle n , a head k is upset on the shank by a head ram p , the internal annular surface i of the head k being free from burs.

- 10 According to the present invention, behind the enclosed matrix is arranged a sleeve q , which is prevented from movement longitudinally by a collar or shoulder r . The sleeve collar r is located in a recess at the back of 15 the matrix and bears against the anvil c , which surrounds the cylindrical sleeve member q . For the guiding of the ejecting needle n the sleeve has a central longitudinal bore t . The latter is connected by two slots v with 20 two lateral longitudinal bores u . In the slots v , lateral lugs x on the needle head are guided. These lugs prevent the needle from rotating. The intermediate piece, which has to drive the needle before it, has a cross section which fits accurately into the three ducts 25 t , u , u and into the slots v that connect them with one another. With a central longitudinal bulb or swelling t' are connected by means of connecting bridge pieces v' two lateral longitudinal bulbs or swellings u' . The diameter of the longitudinal ducts u , and therefore of the marginal bulbs u' of the intermediate piece, can be made considerably greater than the diameter of the central duct t and 30 of the central bulb t' , which is determined by the thickness of the shank s and of the needle n . The total cross-sectional area of the intermediate rail can therefore be made, for any desired length of the shank s , so great 35 that the part of it which projects rearwards without lateral support to a distance at least equal to the length l of the bolt shank at the commencement of the ejecting operation cannot buckle under the pressure of the push rod o , which has to overcome the jamming of the 40 shank s .

The shape of the cross section of the intermediate rail and of the guiding passage thereof may differ at will from those of the constructional example illustrated, provided they 45 give the requisite resistance to buckling.

Thus according to Fig. 10 the marginal bulbs u' embedded in the sleeve are replaced by longitudinal flanges u'' , which are attached to longer transverse bridge pieces v'' and guided on parallel side surfaces q' of the sleeve q . The needle n would under these circumstances have to be made longer by such an amount that the intermediate rail need not 50 penetrate into the collar r , for the latter should not be similarly slotted. Altogether the intermediate rail is of such a length L that even when very long headed bolts are 55 being upset it finds a sufficiently long guide 60 in the sleeve q . Hence merely by pressing,

headed bolts with a press mark free from burs on the inner side i of the head, can be manufactured with shanks of which the length l exceeds eight times the diameter d of the shank, and up to fourteen times the diameter of the shank and even more, without it being necessary, after upsetting the bolt head, to remove burs by a subsequent turning operation. This remedies a defect that has for a long time been keenly felt in the pressing of 75 bolts heads.

What I claim is:—

1. An ejecting implement for headed bolts that have been cold pressed in a one-part matrix, comprising an ejecting needle, adapted to eject the bolt from the matrix after its shank has become jammed therein by the forming of its head, an intermediate piece adapted to drive said ejecting needle before it, a sleeve rigidly secured behind the closed 80 matrix and adapted to guide said ejecting needle and said intermediate piece, and a push rod adapted to exert longitudinal pressure upon said intermediate piece and thereby upon the ejecting needle to eject the bolt from 85 the matrix the longitudinal bore of said sleeve being connected with additional bores adapted to form lateral supports for said intermediate piece.

2. An ejecting implement for headed bolts that have been cold pressed in a one-part matrix, comprising an ejecting needle, adapted to eject the bolt from the matrix after its shank has become jammed therein by the forming of its head, an intermediate piece 90 adapted to drive said ejecting needle before it, a sleeve arranged behind the closed matrix, and adapted to guide said ejecting needle and said intermediate piece, an abutment on said sleeve embedded in a recess of the said matrix 95 adapted to prevent said sleeve from being moved longitudinally, and a push rod adapted to exert longitudinal pressure upon said intermediate piece and thereby upon the ejecting needle to eject the bolt from the matrix 100 the longitudinal guiding bore of the said sleeve being connected with additional guiding ducts adapted to form lateral supports 105 for said intermediate piece.

3. An ejecting implement for headed bolts 110 that have been cold pressed in a one-part matrix, comprising an ejecting needle, adapted to eject the bolt from the matrix after its shank has become jammed therein by the forming 115 of its head, an intermediate piece adapted to drive said ejecting needle before it, said intermediate piece having a cross section comprising a bulb-like central portion and enlarged outer portions connected with said central portion by bridge pieces, a sleeve rigidly secured behind the closed matrix, said sleeve being formed with an axial duct 120 adapted to guide said ejecting needle and with further guiding ducts parallel to said axial duct and connected with it by slots for 125 130

guiding said intermediate piece, and a push rod adapted to exert longitudinal pressure upon said intermediate piece and thereby upon the ejecting needle to eject the bolt from the matrix.

5 4. An ejecting implement for headed bolts that have been cold pressed in a one-part matrix, comprising an ejecting needle, adapted to eject the bolt from the matrix after its shank has become jammed therein by the forming of its head, an intermediate piece adapted to drive said ejecting needle before it, said intermediate piece having a cross section comprising a bulb-like central portion and enlarged outer portions connected with said central portion by bridge pieces, a sleeve arranged behind the closed matrix, said sleeve being formed with an axial duct adapted to guide said ejecting needle and with further guiding ducts parallel to said axial duct and connected with it by slots for guiding said intermediate piece, an abutment on said sleeve adapted to prevent it from being moved longitudinally, and a push rod adapted to exert longitudinal pressure upon said intermediate piece and thereby upon the ejecting needle to eject the bolt from the matrix.

20 5. An ejecting implement for headed bolts that have been cold pressed in a one-part matrix, comprising an ejecting needle, adapted to eject the bolt from the matrix after its shank has become jammed therein by the forming of its head, an intermediate piece adapted to drive said ejecting needle before it, said intermediate piece having a cross section comprising a bulb-like central portion and enlarged outer portions connected with said central portion by bridge pieces, a sleeve arranged behind the closed matrix, an abutment on said sleeve adapted to prevent it from being moved longitudinally, the sleeve being formed with an axial duct adapted to guide the ejecting needle and with further guiding ducts parallel to said axial duct and connected with it by slots for guiding the intermediate piece, said further ducts extending radially out to the periphery of the sleeve, and longitudinally right up to but not through the abutment on the sleeve, and a push rod adapted to exert longitudinal pressure upon said intermediate piece and thereby upon the ejecting needle to eject the bolt from the matrix.

45 6. An ejecting implement for headed bolts that have been cold pressed in a one-part matrix, comprising an ejecting needle, adapted to eject the bolt from the matrix after its shank has become jammed therein by the forming of its head, an intermediate piece adapted to drive said ejecting needle before it, said intermediate piece having a cross section comprising a bulb-like central portion and enlarged outer portions connected with said central portion by bridge pieces,

a sleeve arranged behind the closed matrix, an abutment on said sleeve adapted to prevent it from being moved longitudinally, the sleeve being formed with an axial duct adapted to guide the ejecting needle and with further guiding ducts parallel to said axial duct and connected with it by slots for guiding the enlarged outer portions of the intermediate piece, said further ducts being formed by flattenings produced on opposite sides of the sleeve, and longitudinally right up to but not through the abutment on the sleeve, and a push rod adapted to exert longitudinal pressure upon said intermediate piece and thereby upon the ejecting needle to eject the bolt from the matrix.

In testimony whereof I have signed my name to this specification.
